METHOD FOR FORMING MUSICAL STRINGS

Lewis Edward Wackerle, Chicago, Ill.

Application April 20, 1940, Serial No. 330,804

8 Claims. (CL 57—160)

The present invention relates to methods and apparatuses for forming musical strings and more particularly musical strings having a heat setting material as an element thereof such as, for example only, musical strings as set forth in applicant's copending U. S. application Ser. No. 257,256, of which the present application is a continuation in part.

The principal object of the present invention is to provide a method and apparatus therefor for the creation of a musical string having a heat setting or hardening material forming a coating for one or more metallic elements thereof.

A further object of the present invention is to provide a method for preparing musical strings wherein the heat setting material forming a part thereof can be hardened and aged during the formation of the complete string and thereby connecting the various elements of which the string consists in a permanent, aged and interlocked state.

Another and equally important object of the present invention is to provide an apparatus for forming or repairing musical strings wherein the thermo-setting or thermo-softening materials used in the construction of the string may be heat treated during the formation or repairing of the string.

Other important objects of the present invention will be in part pointed out and in part obvious from the following detailed description of the accompanying drawing.

In the drawing:

Fig. 1 is a side plan view of one form of apparatus for carrying out the present invention.

Fig. 2 is a side plan view of a modified form of apparatus for forming musical strings.

Fig. 3 is a plan view of a third modification of apparatus for forming musical strings.

Fig. 4 is an enlarged vertical cross sectional detail view of a portion of the apparatus shown in Figs. 2 and 3, and

Fig. 5 is an enlarged side detail view of a musical string in the process of being formed.

Referring now more particularly to the accompanying drawing wherein like and corresponding parts throughout the several views are designated by similar reference characters, numeral 1 indicates a string formed from electric resistance metallic material which is used as the base core for the forming of musical strings, as more fully set out in the aforementioned copending application, and upon which is applied a coating 2 which may consist of any thermoplastic or thermo-setting plastic, for instance, synthetic resins or other

materials which can be cured, aged or hardened by applying heat thereto and which are preferably, although not necessarily, electrical insulators. Numeral 3 refers to a metallic band which is wound upon the insulating coating 2 and connected thereto by cement or by contact with the coating. This particular string construction is, however, for example only.

10 A pair of hooks 4, each formed upon the end of a shaft 5 which is rotatably mounted through and supported by a bearing 6, has looped portions of wire 1 connected thereto. The outer end of either or both of the shafts 5 have a member for rotating the shaft connected thereto, such as, for example, a pulley 7 connected to a motor or other means by an endless belt.

15 Each of the bearings 6 are positioned upon an electrical insulating plate 8 and connected by means of wires 9 and 10 to an electrical transformer 11, which in turn is connected to a general electrical circuit.

20 In the formation of musical strings, the wire 1 is rotated by its connection to hooks 4, which are in turn each rotated by their shafts 5 due to the movement of pulleys 7, or in the apparatus, such as shown in Fig. 1, by means of a pulley 7 operating upon one shaft 5 and the rotation of the wire 1 and its connection to the other shaft 5 by the hook 4 thereof. A plastic, plastic fibered by the 25 addition of silk or cotton or both thereto, or other material can at that time be applied to the rotating wire 1, whereupon, a smooth and rounded coating therefor can be formed. While the coating is being applied, current is supplied to the 30 bearings 6 by their wires 9 and 10 from the adjustable transformer 11 in the amount found to be most desirable for the particular materials used. The current passes from one bearing 6 through the shaft 5 supported thereby to the wire 1 and from there to the other shaft 5 to the bearing 35 in contact therewith, thus completing the circuit, but wire 1, due to its low resistance to the passage of current, will be heated and, in the case of a thermo-setting material, will harden the coating 2 through the shaft 5 supported thereby to the wire 1 and from there to the other shaft 5 to the bearing 30 in contact therewith, thus completing the circuit, but wire 1, due to its low resistance to the passage of current, will be heated and, in the case of a 40 thermo-setting material, will harden the coating 2 by driving the volatile materials in the coating 2 outwardly from the periphery thereof. During the thermo-setting of the coating 2, the band 3 can be readily applied to the rotating coating 2 and will adhere thereto before the coating 2 is 45 fully hardened. In this manner, coating 2 will be firmly connected to both wire 1 and band 3 and, at the same time, will be completely aged for preventing the formation of cracks therein as 50 well as permitting the elements 1, 2 and 3 from becoming disassociated later on due to the aging.

that is, further setting and hardening of the coating 2. Additional coatings can be applied to the metallic elements of the musical string and several layers of metallic elements can be applied, one upon the other, before the coating with the insulating material or between successive coatings, but it is to be noted that an essential and indivisible part of the musical string is used for the heating of the insulating coating.

The additional metallic coatings can be connected to the electric current by contact with wire 1 at two points thereof and, in this manner, heat can be applied to successive coatings or to both sides of a coating, such as by connecting the ends of band 3 to the loops of wire 1, thus heating 15 coating 3 from both sides thereof.

Musical strings having a thermoplastic coating can be repaired with the present apparatus by applying heat to said plastic by the metallic element and thereby permitting the tightening or 20 correction of the position of the several elements relative one to the other.

In Fig. 2 of the drawing is shown a modified form of apparatus which has the current passing from the transformer 11 by wire 9 to a bearing 6 in a similar manner to that shown and described for Fig. 1, but the opposite end of the wire 1 is connected to wire 10 by means of a brush 15 supported from bearing 6 by an arm 16, which brush 15 contacts a cylinder 13 which has the hook 12 connected thereto. As best shown in Fig. 4 of the drawing, an insulating sleeve 18 encases shaft 14 which is, in turn, rotatably supported through bearings 6, and sleeve 18 has the bore of cylinder 13 encasing the same. Cylinder 13, which is formed from an electrical conducting material, is thereby insulated from shaft 14 by sleeve 18 and receives current from brush 15, which it passes to hook 12 and from there to wire 1 for completing the circuit when current is passed by the transformer 11 in amounts as desired. An electrical insulating sheet 17 supports both of bearings 6 for insulating the same against possible contact with a ground.

In Fig. 3 of the drawing, the wire 1 receives its current from hooks 12 which are connected to cylinders 13. Cylinders 13 receive their current by brushes 15, which brushes are each connected by one of the wires 9 and 10 to the transformer 11 and the cylinders 13 are rotatably carried with shafts 14 and sleeves 18, as shown in Fig. 4. In both of the modifications of Figs. 2 and 3, the shafts 14 can be rotated by means of a pulley or other rotating instrumentalities and the brushes 15 are maintained in a fixed position by arms 16 but contact the rotating cylinder 13. However, the arrangement of Fig. 3 can be mounted upon a metal support or the like, without the bearings 6 being grounded and this particular modification has that advantage over the 60 other devices disclosed herein.

Musical strings of varying constructions can be rapidly and completely formed by the present apparatus, which strings will maintain their delicate balance, weight, flexibility and correct size throughout their life, thereby assuring that the string will at all times be in the best playing condition possible. Further, the string can be

formed upon one apparatus while being maintained in a straight and extended position. However, musical strings of other constructions than that disclosed in Fig. 5 can be readily formed 5 upon the present apparatus and by following the general idea as set forth herein.

The apparatus can be readily modified but such modifications thereof as come within the scope of the appended claims are deemed to be a part 10 of the present invention.

I claim:

1. A method of producing a musical string consisting of heating a metallic wire by passing electrical current therethrough and applying a coating of a thermo-setting material to said heated wire.

2. A method of producing a musical string consisting of heating a metallic wire, covering said heated wire with a thermo-setting material and applying a metallic skin to said coating before the same is completely hardened.

3. A method of producing a musical string having metallic and thermo-setting elements consisting of passing an electric current through 25 said metallic elements for heating the same and conducting the heat from said metallic elements to said thermo-setting elements.

4. A method of producing a musical string consisting of rotating an extended metallic wire, passing an electric current through said string for heating the same and encasing said heated string with a heat-setting material while said string is rotating.

5. A method of producing a musical string consisting of rotating a metallic wire, heating said rotating wire and encasing said heated rotating wire in a series of coatings of thermo-setting material and metallic material.

6. A method of repairing a musical string having a metallic element and a thermoplastic coating therefor consisting in maintaining said string in an extended position, passing an electrical current through said metallic element for heating said element and said coating, and adjusting the metallic element relative to said coating while heated.

7. A method of producing a composite musical string which consists in retaining a metallic core in an extended position, jointly heating and rotating said core while in its extended position, winding a metallic wrapping upon said core, applying a heat-curing phenolic plastic to said core and between the rovings of said metallic wrapping and winding a second metallic wrapping upon said first mentioned metallic wrapping and said phenolic plastic.

8. A method of producing a composite musical string which consists in retaining a metallic core in an extended position, rotating said core while in its extended position, electrically heating said core while rotating the same, applying a heat-curing phenolic plastic to said core, winding a metallic wrapping upon said phenolic plastic for electrically insulating said metallic wrapping from said metallic core and causing the phenolic plastic to exude through the rovings of said metallic wrapping.

LEWIS EDWARD WACKERLE.
